UNITED STATES PATENT OFFICE.

GEORGE MASSEY, OF BEECROFT, NEW SOUTH WALES, AUSTRALIA.

HYDRAULIC ELEVATOR.

1,276,390.

Specification of Letters Patent. Patented Aug. 20, 1918.

Application filed April 3, 1916. Serial No. 88,600.

To all whom it may concern:

Be it known that I, GEORGE MASSEY, a citizen of the Commonwealth of Australia, residing at Welham street, Beecroft, in the 5 State of New South Wales, Australia, have invented certain new and useful Improvements in Hydraulic Elevators, of which the following is a specification.

This invention is for the purpose of controlling the working or running of hydraulic elevators by an electrically operated gear which will impart motion to the main hydraulic valve in place of the hand rope or other similar and well known devices herebefore in use; and which will admit of the 15 elevator being worked under the control of the car switch.

In order that my invention may be easily understood reference will now be made to the accompanying drawings in which—

Figure 1 is a side elevation and Fig. 2 is an end elevation of the operating gear as applied to the main hydraulic valve of an elevator the power water for the working 25 of which is of low pressure, that is of about 50 to 60 lbs. to the square inch.

Fig. 3 is a plan of a modified gear.

Fig. 4 is a side elevation on line AB of Fig. 3 showing position of gear when the 30 car is stationary.

Fig. 5 is a side elevation on line CD of Fig. 3 showing position of gear when the car is coming down.

Fig. 6 is a side elevation showing position 35 of gear when the car is going up.

Fig. 7 is an end elevation of the main hydraulic valve showing the side links connecting the actuating lever with the perforated tubular spindle which passes 40 through the main hydraulic valve.

Fig. 8 is a plan of the gear showing a chain sprocket wheel secured on to the boss or sleeve of the clutch in lieu of the worm wheel.

Fig. 9 is an end view showing the modified 45 positions of the electric switches and also of the rope guide pulleys.

Fig. 10 shows diagrammatically one convenient arrangement of electrical connections.

Figs. 3, 4, 5, 6, 7 and 8 illustrate the arrangement of the gear when applied to elevators using the power water at the usual pressure of from 700 to 750 lbs. to the square 55 inch.

E is a shaft supported by its bearings E¹

and E²; F is a drum which is secured upon the shaft E; to the periphery of which the one end of a rope F¹ is attached at or near a position shown by F²; G is a toothed wheel secured upon the shaft E; H is a worm wheel secured upon the extended boss of the electro-magnetic clutch I which is free upon the shaft E when not magnetically acted upon by the armature I¹; the armature I¹ which revolves with the shaft E is capable of sliding endwise thereon either toward or from the face of the clutch when influenced either by the magnetic field or the coil spring J; K is the feather key fitting in the 60 keyways of the shaft E and the armature I¹; L and L¹ are the two slip rings by which the electric current is led to and from the coil M; N is an electric motor whose armature shaft N¹ is secured into the wheel or pulley 70 of the magnetic motor brake N² and also into the worm N³ which meshes with the worm wheel H; O is a lever one end of which is attached to the toothed sector O¹ which meshes with the toothed wheel G 75 while the other end is pivoted to the base or wall plate of the main hydraulic valve P; the two side links P¹, P² connect the lever O with the perforated tubular spindle P² of the hydraulic valve P; Q and Q¹ are two 80 lever electric switches arranged in the electric circuit between the car main switch and the motor N together with its brake N².

Fig. 10 shows one method of connecting up the parts electrically. When the switch 90 2 in the car is moved to the left it closes the circuit through the coil in the electromagnetic clutch I, I¹, and also through the circuit including the magnetic brake N², the switch Q¹, the switch Q, and the motor N as 95 will be readily seen from Fig. 10. When the switch 2 is moved to the right it closes circuits through the same parts but the current passes through the motor N in the opposite direction and thus reverses its direction of 100 rotation.

The magnetic brake N² is arranged so that when current passes through same the brake is off and vice versa.

The cycle of operations will be as follows—that is—assuming that the car is stationary and that the various parts of the gear are as shown by Fig. 4 and also that an up trip is to be made by the car then the electric current when switched on by putting 105 over the car switch into the “up” position will energize the coil M through the slip

rings L and L¹ and by the magnetism thereby produced will pull the armature I¹ along the shaft E hard into contact with the face of the clutch I when the motor N will commence to run and turn the shaft E together with the clutch, the worm wheel, the toothed wheel and the drum in a clockwise direction which will by means of the toothed sector raise the lever O and its attached perforated 10 tubular spindle of the hydraulic valve P and so admit the power water on to the hydraulic ram when the car will commence its upward trip; the turning of the shaft E in the direction stated whereby the rope F¹ is coiled upon the left hand side of the drum F and the weight is raised, will continue until the tappet stud F² presses the lever arm of the switch Q into the position shown by Fig. 6 whereby the circuit will be opened; the 15 brake N² will be applied and the motor N will stop. With the gear as shown by Fig. 6 the car will continue on its upward journey until it approaches the floor or position where it is to be stopped when the car 20 switch will be put into the "off" position shown in Fig. 10 which cuts out the current from the slip rings and deenergizes the clutch I thus destroying the frictional friction between its poles and armature and allowing the weight R by means of the rope 25 P¹ to bring back the valve lever O and drum F into the position shown by Fig. 4.

From the foregoing description it will be evident that the downward journey of the 30 car may be brought about by putting over the car switch into the "down" position when the motor and all other parts of the gear will travel in the opposite direction into the position shown by Fig. 5.

Fig. 8 shows a modification in the arrangement for driving the gear by fixing a chain sprocket wheel S upon the extended boss of the clutch I in lieu of the worm wheel H and running the gear by a chain 45 from a wheel upon the worm shaft of a motor which may be in some instances more suitably erected some little distance away.

The foregoing description relates to the gear when applied to hydraulic elevators 50 worked by power water of from 700 to 750 lbs. pressure to the square inch.

When the gear is applied to hydraulic elevators worked by power water of about 55 to 60 lbs. pressure to the square inch the larger volume of water that must be admitted on to the piston of the lifting cylinder necessitates a main hydraulic valve of much larger capacity. This involves increased diameter and stroke of the pistons 60 of this valve and to allow of this increased length of stroke a straight toothed rack T is attached to the upper end of the valve rod W which meshes with the tooth wheel G upon the shaft E as shown in Figs. 1 and 2.

In some installations the position of the

hydraulic valve may not be high enough above the floor level to provide for a sufficient run of the weight R, in such a case it will be advisable to arrange the two rope guide wheels U and U¹ above the shaft E 70 and the switches Q and Q¹ below, and provide for carrying the rope F¹ overhead upon suitable pulleys and thence down to the weight R as shown by Fig. 9.

Having thus particularly described the 75 nature of my invention and in what manner the same is to be performed I claim:

1. In an electrically operated gear for controlling hydraulic elevators the combination of a valve controlling the pressure 80 water, a shaft, means for moving said valve by said shaft, an electric motor, an electromagnetic clutch between said motor and said shaft, means for rendering said clutch operative or inoperative, a drum connected 85 with said shaft, means tending to return said drum to a predetermined position, and means operated by said drum, after it moves away from said predetermined position, to stop said motor. 90

2. In an electrically operated gear for controlling hydraulic elevators the combination of a valve controlling the pressure water, a shaft, means for moving said valve by said shaft, an electric motor, an electromagnetic clutch between said motor and said shaft, means for rendering said clutch operative or inoperative, a drum connected with 95 said shaft, a weight connected to said drum and tending to return the same to a predetermined position, a switch arranged in the circuit of said motor, and means on said drum adapted to open said switch after the drum moves away from said predetermined position. 100

3. In an electrically operated gear for controlling hydraulic elevators the combination of a valve controlling the pressure water, a shaft, means for moving said valve by said shaft in either direction according 110 to the direction of movement of the shaft, a reversible electric motor, an electromagnetic clutch between said motor and said shaft, means for rendering said clutch operative or inoperative, a drum connected 115 with said shaft and adapted to move in either direction from a mid-position, means tending to return said drum to said mid-position, a pair of switches arranged in the circuit of said motor, and means on said drum adapted to open one of said switches after the drum moves in either direction away from said mid-position. 120

4. In an electrically operated gear for controlling hydraulic elevators the combination of a valve controlling the pressure water, a shaft, a pinion mounted on said shaft, a rack engaging said pinion and connected to the valve said valve being in its mid-position when the rack is in its mid- 125 130

position with relation to said pinion, a reversible electric motor, an electro-magnetic clutch between said motor and said shaft, a main switch controlling a circuit for rendering said clutch operative or inoperative, a magnetic brake, means whereby said main switch also controls a circuit through said magnetic brake and said motor, a drum connected to said shaft, means tending to 10 turn said drum to a predetermined position,

and means operated by said drum, after it moves in either direction away from said predetermined position, to break the circuit through said magnetic brake and motor.

In testimony whereof I affix my signature 15 in the presence of two witnesses.

GEORGE MASSEY.
